Fig. 2.

Fig. 1.

Fig. 3.

FIGURE 1 is a front perspective view of a refrigerator cabinet or similar article showing our new design thereof; FIGURE 2 is an end elevational view thereof;

FIGURE 3 is a rear elevational view thereof;

FIGURE 4 is an enlarged fragmentary elevational view of one of the grille panels;

FIGURE 5 is a vertical sectional view taken on line 5-5 of FIGURE 4;

FIGURE 6 is a front elevational view of a modified form of the refrigerator cabinet or similar article shown in FIGURES 1 to 3, the ends and rear thereof being essentially the same as those of the cabinet shown in FIGURES 1 to 3; and

FIGURE 7 is a front elevational view of another modified form of the refrigerator cabinet or similar article shown in FIGURE 1, the ends and rear thereof being essentially the same as those of the cabinet shown in FIGURES 1 to 3.

The dominant features of our design reside in the portions shown in full lines.

We claim:

The ornamental design for a refrigerator cabinet or similar article, substantially as shown and described.
